CLAIM

The ornamental design for a shoe rack, as shown and described.

DESCRIPTION

FIG. 1 is a perspective view of a shoe rack showing my new design;

FIG. 2 is a front plan view thereof;

FIG. 3 is a right plan view thereof;

FIG. 4 is a left plan view thereof;

FIG. 5 is a top plan view thereof;

FIG. 6 is a bottom plan view thereof; and,

FIG. 7 is a rear plan view thereof.

The broken lines are for the purpose of illustrating the environment of the article only and form no part of the claimed design.
